UNITED STATES PATENT OFFICE.

FREDERICK M. THOMPSON, OF DANBURY, CONNECTICUT.

LOCK.

SPECIFICATION forming part of Letters Patent No. 766,472, dated August 2, 1904.

Application filed March 24, 1904. Serial No. 199,689. (No model.)

To all whom it may concern:

Be it known that I, FREDERICK M. THOMPSON, a citizen of the United States, residing at Danbury, county of Fairfield, State of Connecticut, have invented a new and useful Lock, of which the following is a specification.

My invention has for its object to produce a lock adapted for general use, and especially adapted for use upon the doors of stores and public buildings where it is desirable that certain persons should have the privilege or duty of unlocking the door, but not of locking it, that others should have the privilege or duty of locking it, but not of unlocking it, and that still other persons should have the privilege of both unlocking and locking it. In other words, I provide a lock having three keys or sets of keys, which I will identify as "No. 1," "No. 2," and "No. 3," No. 1 being a master-key and both unlocking and locking; No. 2 having the power of unlocking only, and No. 3 the power of locking only.

As an illustration of the operation of my novel lock, suppose in the case of a store or public building that it is necessary that certain clerks, employees, or occupants have the power to effect an entrance at any time, but that it is extremely undesirable, as in the case of stores, that they have the privilege of entering it outside of business hours. The proprietors, the managers, and such persons as they choose to trust have No. 1 keys, which enable them to enter and leave the building at any time, as they can both unlock and lock the door. An employee or employees whose duty it is to open the building are provided with No. 2 keys. This enables them to unlock the door, but compels them to stay there after it has once been unlocked or else to notify a person having a key that will lock the door. As there is always some person whose duty it is to close the building at night after all others have left it, this person is provided with a No. 3 key, which enables him to lock the building, but does not permit him to unlock it. By providing employees of a store with No. 2 or No. 3 keys in accordance with the requirements of their duties the owner or manager is assured that these duties may

be attended to without inconvenience and is also assured that there will be no entrance of the store except at the proper times, as the person who unlocks the door must remain until others come or notify a person having a locking-key, as he will be unable himself to lock the door.

With these and other objects in view I have devised the novel lock which I will now describe, referring to the accompanying drawings, forming a part of this specification, and using reference characters to indicate the several parts.

Figure 1 is a plan view, the face-plate of the case being removed, illustrating a form of the invention in which a single tumbler is provided with both unlock and lock stops—that is, a stop that is engaged by a No. 2 key to prevent locking therewith and a stop that is engaged by a No. 3 key to prevent unlocking therewith—the bolt being in the retracted position; Fig. 2, a detail sectional view on the line indicated by 2 in Fig. 1, illustrating the act of locking or unlocking with a No. 1 key; Fig. 3, a detail view illustrating the act of unlocking with a No. 2 key and in dotted lines the position of the tumbler when an attempt is made to throw the bolt with a No. 2 key; Fig. 4, a detail view illustrating the act of locking with a No. 3 key and in dotted lines the position of the tumbler when an attempt is made to retract the bolt with a No. 3 key; Fig. 5, a perspective of the single tumbler in this form of the invention detached; Fig. 6, an inverted plan view of the tumbler detached; Fig. 7, a plan view with the face-plate removed, illustrating a form of the invention in which the unlock and lock stops adapted to be engaged by No. 2 and No. 3 keys, respectively, as before, are formed on independent tumblers, the bolt being in the retracted position; Fig. 8, a perspective of the tumblers in Fig. 7 detached; Fig. 9, a detail sectional view similar in character to Fig. 2, but corresponding with the form of lock in Fig. 7, illustrating the act of locking or unlocking with a No. 1 key; Fig. 10, a similar view illustrating the act of unlocking with a No. 2 key and in dotted lines the position of

the unlock-stop on one of the tumblers when an attempt is made to throw the bolt with a No. 2 key; Fig. 11, a similar view illustrating the act of locking with a No. 3 key and in dotted lines the position of the lock-stop on one of the tumblers when an attempt is made to retract the bolt with a No. 3 key; Fig. 12, a plan view with the face-plate removed, illustrating a form of the invention in which independent tumblers are provided with recesses the effect of which is to so place the tumblers that stops thereon will be engaged by an abutment on the bolt to prevent locking with a No. 2 key and to prevent unlocking with a No. 3 key, the bolt being in the act of being thrown or retracted by a No. 1 key; Fig. 13, a detail sectional view on the line indicated by 13 in Fig. 12, illustrating the act of locking or unlocking with a No. 1 key; Fig. 14, a detail plan view illustrating the action of the unlock-stop on one of the tumblers when an attempt is made to throw the bolt with a No. 2 key; Fig. 15, a detail view showing the normal position of the tumblers—that is, when the bolt is either thrown or retracted; Fig. 16, an inverted plan view of the tumbler corresponding with Fig. 15; Fig. 17, a detail plan view corresponding with Fig. 14, illustrating the action of the lock-stop on one of the tumblers when an attempt is made to retract the bolt with a No. 3 key; Fig. 18, a detail sectional view similar in character to Fig. 10, but corresponding with the form of lock in Figs. 12 to 17, inclusive, illustrating the act of unlocking with a No. 2 key and in dotted lines the position of the unlock-stop on one of the tumblers when an attempt is made to throw the bolt with a No. 2 key; and Fig. 19 is a view similar in character to Fig. 11, illustrating the act of locking with a No. 3 key and in dotted lines the position of the lock-stop on one of the tumblers when an attempt is made to retract the bolt with a No. 3 key.

45 20 denotes a lock-case, and 21 a bolt having a recess 38, the opposite sides of which are respectively engaged by a projection on a key in throwing or retracting the bolt. It will be obvious, however, that the special style of 50 the case and of the bolt are of no importance so far as the principle of the invention is concerned.

55 22 denotes a key which will both throw and retract the bolt and which for convenience I have termed the "No. 1" key; 23, a key that will retract the bolt, but will not throw it, and which for convenience I have termed the "No. 2" key, and 24 a key that will throw the bolt, but will not retract it, and which for 60 convenience I have termed the "No. 3" key.

In the form of the invention illustrated in Figs. 1 to 6, inclusive, but a single tumbler is used, which I have indicated by 25. This tumbler is pivoted upon a stud 26 and is shown 65 as retained in the operative position by a coil-

spring 27, which bears against the tumbler and against an abutment 28 upon the case. The tumbler is also provided with a lug 29, which is engaged by a lug 30 on the bolt to prevent the bolt from being thrown except when the tumbler is lifted by a No. 1 or a No. 3 key or retracted except when the tumbler is lifted by a No. 1 or a No. 2 key.

The essential feature of the several forms of the invention is that I provide stops upon the tumbler or tumblers which may be engaged by the keys or by a stump on the bolt to prevent the bolt from being retracted except by a No. 1 or a No. 2 key and to prevent it from being thrown except by a No. 1 or a No. 3 key. In the form of the invention illustrated in Figs. 1 to 6, inclusive, these stops are both formed upon tumbler 25. 31 indicates a stop upon the tumbler which I term the "unlock-stop," for the reason that it retains the bolt in the retracted or substantially the retracted position against a No. 2 key, which can only unlock—that is, retract the bolt—and 32 indicates a stop upon the tumbler which I term the "lock-stop," for the reason that it retains the bolt in the thrown or substantially the thrown position against a No. 3 key, which can only lock—that is, throw the bolt. It will be noted that these stops are abrupt shoulders facing each other and that back of the stops are inclines, (indicated, respectively, by 33 and 34.) These inclines pass into notches in the bits of the keys, as will presently be fully explained. Between the stops is a groove or passage 76, which receives one of the projections on the bits of the keys.

Turning now to Fig. 2, the essential features of a No. 1 key, which I have indicated by 22 for this form of the invention, are recesses 35 at the end of the bit, on opposite sides thereof, which permit the key to pass stop 32 upon the tumbler in the act of unlocking, projections 36, which enter groove 76 in the tumbler and by engaging the bottom of said groove lift the tumbler in the act of locking or unlocking and also engage the wall of recess 38 in the bolt to throw or retract the bolt, and a recess 37 between projections 36, which permits the key to pass stop 31 on the tumbler in the act of locking, it being understood, of course, that one of the recesses 35 and one of the projections 36 are operative when the key is inserted from one side of the door, the other recess 35 and projection 36 being operative when the key is inserted from the other side of the door. In operating a No. 1 key, therefore, to throw the bolt the tumbler is lifted by the engagement of one of the projections 36 with the bottom of groove 76. Recess 37 permits the key to pass stop 31 freely, and the other projection 36 engages the forward wall of recess 38 in the bolt and moving along said wall throws the bolt. The instant the bolt is 130

thrown lug 29 on the tumbler drops down behind lug 30 on the bolt and locks the latter at the thrown position. In retracting the bolt the operation is the same except that the 5 rear wall of recess 38 in the bolt is engaged by the projection on the bit of the key to retract it.

The No. 2 key, which is an unlocking-key only and which I have indicated by 23 for this 10 form of the invention, (see Fig. 3,) differs from the No. 1 key in the omission of recess 37. The recesses 35 on the opposite sides of the bit are the same as before; but as there is a continuous projection between these recesses I will 15 indicate that projection by 39. In retracting the bolt with a No. 2 key incline 33 on the tumbler is engaged by projection 39 to raise the tumbler. One of the recesses 35 permits the key to pass stop 32, and projection 39 engages the rear wall of recess 38 in the bolt and 20 retracts it. The instant the bolt is retracted lug 29 on the tumbler drops down before lug 30 on the bolt and locks the latter at the retracted position, as in Fig. 1. Any attempt 25 to throw the bolt with this key, however, is thwarted through the engagement of projection 39 on the key with stop 31 on the tumbler. (See dotted lines, Fig. 3.)

The No. 3 key, which is a locking-key only 30 and which I have indicated by 24 for this form of the invention, (see Fig. 4,) differs from the No. 1 key in the omission of recesses 35. The recess 37 at the center of the bit is the same as in the No. 1 key; but as the projections on the 35 opposite sides of this recess extend to the sides of the bit I will indicate those projections by 40. In throwing the bolt with a No. 3 key incline 34 on the tumbler is engaged by one of the projections 40 to raise the tumbler. The 40 recess 37 permits the key to pass stop 31, and one of the projections 40 engages the forward wall of recess 38 in the bolt and throws it. The instant the bolt is thrown lug 29 on the tumbler drops down behind lug 30 on the bolt 45 and locks the latter at the thrown position. Any attempt to retract the bolt with this key, however, is thwarted through the engagement of one of the projections 40 on the key with stop 32 on the tumbler. (See dotted lines, 50 Fig. 4.)

In Figs. 7 and 8 I have illustrated the application of the principle of the invention to a form of lock having two or more tumblers. In the present instance I have shown three 55 tumblers, although but two are required to carry out the principle of the invention, the intermediate tumbler merely performing the ordinary function of guarding the bolt—that is, retaining it in either the thrown or retracted 60 position. These tumblers are all pivoted on a stud 26, as in the other form, and are retained in operative position by springs 41, one end of each spring being connected to a tumbler and the other end bearing against an abutment 42 on the case. The tumblers in this

form are provided with openings 43. 44 and 45 denote, respectively, upper and lower projections extending into the openings from opposite sides at the mid-length of the openings. The upper and lower projections on each tumbler are of different lengths, there being between the projections on each tumbler a neck or passage 46 just wide enough to permit a stump 47 on the bolt to pass freely in throwing or retracting the bolt, the bolt being locked in 70 the thrown or retracted position by the engagement of the front or rear ends of the stump with the projections, as indicated in Fig. 7, in which the bolt is shown in the retracted position. As soon, however, as an attempt is 75 made to throw the bolt without raising the tumblers to the proper heights, respectively, to permit the stump to pass through the necks the stump will engage the projections and lock the bolt against further movement, the 80 operation being precisely the same when the bolt is in the thrown position except that the stump will lie in front of the projections instead of behind them, as in Fig. 7. For convenience in illustration I will indicate the upper 85 tumbler as they appear in the drawings by 48, the intermediate tumbler by 49, and the lower tumbler by 50. In this form the unlock-stop—that is, the stop that retains the bolt in the retracted or substantially the re- 90 tracted position against a No. 2 key, which can only unlock—that is, retract—the bolt and which I have indicated by 51—is on tumbler 48, and the lock-stop—that is, the stop that retains the bolt in the thrown or substantially 95 the thrown position against a No. 3 key, which can only lock—that is, throw—the bolt and which I have indicated by 52—is on tumbler 50. These stops are abrupt shoulders, as in the other form; but the corresponding inclines, 100 which I have indicated, respectively, by 53 and 54, are in front of the stops instead of behind them, as in the other form. 55 indicates the No. 1 key for this form, 56 the No. 2 key, and 57 the No. 3 key. In this form of the invention the projections at the ends of the bits of the keys are indicated by 58 and are of the same height in the three keys. The central recess between these projections is, however, 105 relatively deep in the No. 1 and No. 2 keys and relatively shallow in the No. 3 key. I therefore indicate the relatively deep central recesses of the No. 1 and No. 2 keys by 59 and the relatively shallow central recess of the No. 3 key by 60. The recesses at the ends of 110 the bits on opposite sides thereof are relatively deep in the No. 1 and No. 3 keys and relatively shallow in the No. 2 key. I therefore indicate the relatively deep end recesses of the No. 1 and No. 3 keys by 61 and the relatively shallow end recesses of the No. 2 key by 62. In 115 operating a No. 1 key in this form to throw the bolt tumbler 48 is raised by the engagement therewith of the bottom of one of the recesses 61 in the key, tumbler 49 is raised by 120

the engagement therewith of one of the projections 58, and tumbler 50 is raised by the engagement therewith of the bottom of recess 59 in the key, and the bolt is moved forward 5 by the engagement of the other projection 58 on the bit of the key with the forward wall of the recess 38 in the bolt. As soon as the bolt commences to move forward stump 47 on the bolt will pass into the necks or passages 46 10 between the upper and lower projections on the tumblers, so that when the bit of the key in its forward movement comes into alinement with unlock-stop 51 on tumbler 48 said tumbler will be retained in the raised position by 15 the engagement of the end of the upper projection thereon with the top of stump 47, thus retaining said unlock-stop out of engagement with the bit of the key. As soon as the bolt is thrown by the forward movement of the key 20 the tumblers will drop down again and the bolt will be locked in the thrown position by the upper projections on the tumblers, which will drop down behind it. In retracting the bolt the operation is the same except that the 25 rear wall of recess 38 in the bolt is engaged by the projection on the bit of the key to retract it, tumbler 50 being retained at the raised position through the engagement of the end of the upper projection thereon with the top of 30 stump 47 on the bolt, which retains the lock-stop out of engagement with the bit of the key. The No. 2 key for this form of the invention, which is an unlocking-key only and which I have indicated by 56, (see Fig. 10,) differs from 35 the No. 1 key only in that relatively shallow end recesses 62 are substituted for the relatively deep end recesses 61 of the No. 1 key. In retracting the bolt with a No. 2 key the operation is precisely the same as with a No. 40 1 key. Any attempt to throw the bolt with this key, however, is thwarted through the engagement of the end of the bit of the key with unlock-stop 51. This engagement takes place just below the relatively shallow end recess 62, as is shown in dotted lines in Fig. 45 10. It must be understood that in the lock illustrated in Figs. 7 and 8 recesses at the ends of the bit on opposite sides thereof are required for the proper manipulation of the 50 tumblers. The relative shallowness of the end recesses, however, in this form permits the metal below said recesses to serve, in effect, as projections which engage the unlock-stop in an attempt to throw the bolt. The 55 No. 3 key for this form of the invention, which is a locking-key only and which I have indicated by 57, (see Fig. 11,) differs from the No. 1 key only in that a relatively shallow central recess 60 is substituted for the relatively deep central recess 59 of the No. 1 key. In throwing the bolt with a No. 3 key the operation is precisely the same as with a No. 1 key. Any attempt to retract the bolt with this key, however, is thwarted through the 60 65 engagement of the end of the bit of the key

with lock-stop 52. This engagement takes place just below the relatively shallow central recess 60, as indicated by dotted lines in Fig. 11, it being understood that in the lock illustrated central recesses at the ends of the bits of the keys are required for the proper manipulation of the tumblers. The relative shallowness of the central recess, however, in this form permits the metal below said recess to serve, in effect, as a projection, which engages the lock-stop in an attempt to retract the bolt. 75

In Figs. 12 to 19, inclusive, I have illustrated the application of the principle of the invention in a slightly-variant manner to a form of lock having two or more tumblers. In the present instance I have shown three tumblers, although but two are required to carry out the principle of the invention, the intermediate tumbler merely performing the ordinary function of guarding the bolt—that is, retaining it in either the thrown or retracted position. These tumblers are all pivoted on a stud 26, as in the other forms, are retained in operative position by springs 41, as in the second form, and are provided with openings 43, having upper and lower projections of varying length extending into the openings from opposite sides thereof. The bolt is provided with a recess 38, as in both of the other forms, and with a stump 47, as in the second form. For convenience in illustration I will indicate the upper tumbler as they appear in the drawings, by 63, the intermediate tumbler by 64, and the lower tumbler by 65. In this form the unlock-stop—that is, the stop which retains the bolt in the retracted or substantially the retracted position against a No. 2 key, which can only unlock—that is, retract the bolt—is on the upper tumbler, as before, said tumbler being in this form indicated by 63. Instead of providing a special stop for this purpose, however, as in the second form, the tumblers and the bits of the keys are so constructed and arranged relatively to each other that the upper projection on the upper tumbler, (indicated in the present instance by 44^a,) which extends into the opening 43, acts as the unlock-stop—that is, the stop that retains the bolt in the retracted or substantially the retracted position against a No. 2 key. The lock-stop—that is, the stop that retains the bolt in the thrown or substantially the thrown position against a No. 3 key, which can only lock—that is, throw the bolt—is on the lower tumbler, as before, said tumbler being in this form indicated by 65. Instead of providing a special stop for this purpose, however, as in the second form, the tumblers and the bits of the keys are so constructed and arranged relatively to each other that the upper projection on the lower tumbler, (indicated in the present instance by 44^b,) which extends into the opening 43, acts as the lock-stop— 110 115 120 125 130

that is, the stop that retains the bolt in the thrown or substantially the thrown position. 56 denotes the No. 1 key for this form, 67 the No. 2 key, and 68 the No. 3 key. In this 5 form of the invention the projections at the ends of the bits of the keys are indicated by 69 and are of the same height in the three keys. The central recess between these projections is, however, relatively shallow in the 10 No. 1 and No. 2 keys and relatively deep in the No. 3 key. I therefore indicate the relatively shallow central recesses in the No. 1 and No. 2 keys by 70 and the relatively deep central recess in the No. 3 key by 71. The 15 recesses at the ends of the bit on opposite sides thereof are relatively shallow in the No. 1 and No. 3 keys and relatively deep in the No. 2 key. I therefore indicate the relatively shallow end recesses of the No. 1 and 20 No. 3 keys by 72 and the relatively deep end recess of the No. 2 key by 73. It will of course be obvious that the engaging surfaces of the tumblers and the corresponding engaging surfaces of the bits of the keys must be 25 shaped to correspond with each other in order to produce the desired result. In the present instance I have shown tumbler 63 as provided with a curved depression 74 in its engaging surface lying back of or substantially back of 30 the lower projection 45 and have shown tumbler 63 as provided with a similar curved depression 75, lying forward or substantially forward of the lower projection 45. In this 35 form the operation of the No. 1 key in throwing and retracting the bolt, the operation of the No. 2 key in retracting the bolt, and the operation of the No. 3 key in throwing the bolt is precisely the same as in the form last described. The tumblers are all raised by the 40 bits of the keys just sufficiently to place the necks or passages 46 between the projections on the tumblers in alignment with stump 47 on the bolt, so that said stump can pass through them in either direction as the bolt is moved 45 forward or backward, the bolt being locked in both the thrown and retracted positions in the same manner as before. Any attempt to throw the bolt with a No. 2 key, however, is thwarted through the engagement of stump 47 on the 50 bolt with unlock-stop 44^a on tumbler 63, as clearly shown in Fig. 14. (See also Fig. 18.) This result is accomplished through the coaction of one of the relatively deep end recesses 73 in the No. 2 key (indicated by 67) 55 with depression 74 in tumbler 63. The combined effect of the depression in the tumbler and the recess in the key may or may not result in raising the tumbler slightly. The essential feature, however, is that said tumbler 63 cannot be raised high enough by the 60 No. 2 key in an attempt to throw the bolt to raise unlock-stop 44^a on the tumbler above stump 47 on the bolt, so that in the forward movement of the bolt the stump will 65 positively engage this stop, which will effectually

lock the bolt against further forward movement. In retracting the bolt, however, with a No. 2 key the bottom of one of the recesses 73 in the key will engage the under side of the tumbler in front of depression 74 and the 70 tumbler will be raised just sufficiently to permit stump 47 to pass through the neck or passage 46 between the projections in openings 43 in the tumblers.

Any attempt to retract the bolt with a No. 75 3 key is thwarted through the engagement of stump 47 on the bolt with lock-stop 44^b on tumbler 63, as clearly shown in Fig. 17. (See also Fig. 19.) This result is accomplished through the coaction of relatively deep central recess 71 in the No. 3 key, which is indicated by 68, with depression 75 in tumbler 63. The combined effect of the depression in the tumbler and the recess in the key may or 80 may not result in raising the tumbler slightly. 85 The essential feature, however, is that tumbler 63 cannot be raised high enough by the No. 3 key in an attempt to retract the bolt to raise lock-stop 44^b on the tumbler above stump 47 on the bolt, so that in the backward 90 movement of the bolt the stump will positively engage this stop, which will effectually lock the bolt against further backward movement. In throwing the bolt, however, with a No. 3 key the bottom of the recess 71 in 95 the key will engage the under side of the tumbler back of depression 75 and the tumbler will be raised just sufficiently to permit stump 47 to pass through the neck or passage 100 46 between the projections in opening 43.

In each embodiment of the invention shown and described the keys which I have referred to as the No. 2 and the No. 3 key are what may be properly termed "secondary" keys, said two keys differing from each other and 105 one being adapted to only project the bolt and the other being adapted to only retract the bolt after it has been projected. It will be also understood that in each form or embodiment of the invention the tumbler mechanism 110 is provided with shoulders or detents which are out of alignment with each other, so that each of the differently and suitably bitted secondary keys will move the bolt in but one direction. In the form illustrated in Figs. 1 115 to 6 these shoulders or detents comprise the stops 31 and 32, in Figs. 7 and 8 such shoulders or detents comprise the stops 51 and 52, and in Figs. 12 to 19 said shoulders or detents comprise the projections 44^a and 44^b, 120 which are left in or thrown out of the path of the stump 47 of the bolt. Of course the said projections 44^a and 44^b are out of alignment with each other because they are carried by different tumblers. 125

Having thus described my invention, I claim—

1. The combination with a lock including a bolt and tumbler mechanism the latter provided with lock and unlock stops, of two sec- 130

ondary keys differing from each other, one for locking and the other for unlocking the bolt, substantially as described.

2. The combination with a lock including a bolt and tumbler mechanism the latter provided with lock and unlock stops, of two secondary keys differing from each other, one for locking and the other for unlocking the bolt, and a master-key for both locking and unlocking the bolt.

3. In a lock, the combination of a bolt, tumbler mechanism therefor, said tumbler mechanism provided with a shoulder or detent for engagement by a key to retract the bolt and a shoulder or detent for engagement by a key to project the bolt, said shoulders or detents being out of alinement with each other whereby a suitably-bitted key will only project said bolt, and a suitably-bitted second key will only retract the bolt.

4. In a lock, the combination of a bolt, tumbler mechanism therefor, said tumbler mechanism provided with a shoulder or detent for engagement by a key to retract the bolt and a shoulder or detent for engagement by a key to project the bolt, said shoulders or detents being out of alinement with each other whereby a suitably-bitted key will only project said bolt, and a suitably-bitted second key will only retract the bolt, a master-key being provided adapted to both project and retract the bolt.

5. In a lock, the combination of a bolt, tumbler mechanism therefor said tumbler mechanism provided with a shoulder or detent for

engagement by a key to retract the bolt and a shoulder or detent for engagement by a key to project the bolt, said shoulders or detents being out of alinement with each other, a key having a bit provided with projections and recesses and adapted to actuate the tumbler mechanism and to only project the bolt, and another key having a bit provided with dissimilar projections and recesses and adapted to actuate the tumbler mechanism and to only retract the bolt.

6. In a lock, the combination of a bolt, tumbler mechanism therefor said tumbler mechanism provided with a shoulder or detent for engagement by a key to retract the bolt and a shoulder or detent for engagement by a key to project the bolt, said shoulders or detents being out of alinement with each other, a key having a bit provided with projections and recesses and adapted to actuate the tumbler mechanism and to only project the bolt, another key having a bit provided with dissimilar projections and recesses and adapted to actuate the tumbler mechanism to only retract the bolt, and a third or master key having a bit provided with projections and recesses differing from both of the other keys and adapted to actuate the tumbler mechanism and to either project or retract the bolt.

In testimony whereof I affix my signature in presence of two witnesses.

FREDERICK M. THOMPSON.
